(57) **CLAIM**

I claim the ornamental design for a grill, as shown and described.

DESCRIPTION

FIG. 1 is a perspective view of a grill in an open configuration, showing the new design;

FIG. 2 is a top plan view of the grill in an open configuration;

FIG. 3 is a front elevation view of the grill in an open configuration;

FIG. 4 is a right side elevation view of the grill in an open configuration;

FIG. 5 is a rear elevation view of the grill in an open configuration;

FIG. 6 is a left side elevation view of the grill in an open configuration;

FIG. 7 is a bottom plan view of the grill in an open configuration;

FIG. 8 is a perspective view of the grill in a closed configuration;

FIG. 9 is a top plan view of the grill in a closed configuration;

FIG. 10 is a front elevation view of the grill in a closed configuration;

FIG. 11 is a right side elevation view of the grill in a closed configuration;

FIG. 12 is a left side elevation view of the grill in a closed configuration;

FIG. 13 is a rear elevation view of the grill in a closed configuration; and,

FIG. 14 is a bottom plan view of the grill in a closed configuration.

The broken lines shown in the drawings depict portions of the grill that form no part of the claimed design.

1 Claim, 13 Drawing Sheets
